(57) **CLAIM**

The ornamental design for an enclosure for a customer premise equipment device, as shown and described.

DESCRIPTION

FIG. 1 is a top, front perspective view of an enclosure for a customer premise equipment device, showing our new design;

FIG. 2 is a bottom, rear perspective view thereof;

FIG. 3 is a top plan view thereof;

FIG. 4 is a bottom plan view thereof;

FIG. 5 is a front elevation view thereof;

FIG. 6 is a rear elevation view thereof; and,

FIG. 7 is a left side elevation view thereof, the right side elevation view is a mirror image thereof.

The broken lines shown in the views are included for the purpose of illustrating portions of the enclosure that form no part of the claimed design. In addition, the surface between the bottom solid line edge and the bottom outermost broken line forms no part of the claimed design.
